UNITED STATES PATENT OFFICE.

WILLIAM E. VAN DORN, OF CHICAGO, ILLINOIS.

MEANS FOR ATTACHING STEEL CAR ENDS.

Original application filed November 19, 1920, Serial No. 425,040. Divided and this application filed February 17, 1921. Serial No. 445,682.

To all whom it may concern:

Be it known that I, WILLIAM E. VAN DORN, a citizen of the United States, residing at Chicago, county of Cook, State of Illinois, have invented a certain new and useful Improvement in Means for Attaching Steel Car Ends, and declare the following to be a full, clear, and exact description of the same, such as will enable others skilled in the art to which it pertains to make and use the same, reference being had to the accompanying drawings, which form a part of this specification.

In my prior application for improvements in corrugated metal car end, filed November 19, 1920, Serial No. 425,040, of which the present application is a division, I have disclosed a novel form of corrugated steel panel possessing great strength and unusually great capacity to resist forces acting transversely to the plane thereof. The present invention has for its object to produce a simple and efficient connection between one or more of such panels and the side members of a car body or the like.

The various features of novelty whereby my invention is characterized will herein-after be pointed out with particularity in the claims; but for a full understanding of my invention and of its object and advantages, reference may be had to the following detailed description taken in connection with the accompanying drawings, wherein:

Figure 1 is an elevation of a box car end embodying my invention;

Fig. 2 is a vertical transverse section through the metal end detached from the car;

Fig. 3 is a section taken approximately on line 3—3 of Fig. 1;

Fig. 4 is a view similar to Fig. 3, on an enlarged scale, of a modification showing only one corner of the car;

Fig. 5 is an elevation of an end of a gondola car embodying my invention;

Fig. 6 is a section taken approximately on line 6—6 of Fig. 5; and

Fig. 7 is a transverse section on line 7—7 of Fig. 5.

In Figures 1 to 3 of the drawings I have illustrated my invention in the form of an end for a box car, the end being made in two panels one arranged above the other. Referring to these figures, 1 and 2 represent respectively the lower and the upper

panels, these being conveniently secured together by a riveted lap joint, 3. Each of the panels is in the form of a flat sheet having a plurality of parallel corrugations extending from the vicinity of one side edge to the vicinity of the other side edge. In the particular arrangement shown, each entire panel, with the exception of a flat marginal rim-like portion is filled with corrugations, the latter being of approximately uniform depth throughout their length.

In accordance with my invention I bend the corrugations lengthwise transversely of the plane of the sheet without bodily bending the sheet so as to give them an arched or bow-shaped formation. This can be accomplished, without unduly deepening the corrugations, by pressing a portion of each corrugation in one direction from the plane of the sheet and the remainder of the corrugation in the opposite direction from said plane, so that each corrugation lies partly on one side of the sheet and partly on the other. Furthermore, by this construction undue stretching of the metal in making the corrugations is avoided. In the arrangement shown, the central section, 4, of each corrugation is pressed outwardly from the plane of the sheet while the two end sections, 5 and 6, are pressed inwardly, all three of the sections being preferably straight. The extreme ends of the corrugations are preferably flattened as indicated at 7, so as to lie in planes which make an obtuse angle with the plane of the sheet.

The metal end is fastened to the sides, 8, of the car in any suitable way. The sides, 8, are illustrated as terminating in corner posts, 9. The flat marginal portions at the sides of the end extend across the posts and are flanged around the same as indicated at 10. Secured to the inner faces of the posts are vertical reinforcing bars, 11, L-shaped in cross section, one flange of each of these bars being conveniently tied to the post and to the flange, 10, by means of bolts, 12, and the other flange being fastened to the end sections, 5, of the corrugations by suitable rivets, 13. Further stiffness may be given to each corner by means of an angle iron, 14, one flange of which is riveted to the member 11 as indicated at 15, and the other of which is bolted through the corresponding side of the car and through the corresponding flange, 10, by means of bolts, 16.

100

105

110

115

120

In Fig. 4 the corrugations are shown as being somewhat longer than in Figs. 1 to 3, the flattened ends of the end sections resting against a correspondingly-shaped surface, 17, on the post 18. In addition to the bolts, 19, passing through the post and the flange 10, there are other bolts, 20, extending through the post and the flat marginal portion of the sheet parallel with the longitudinal axis of the car. A reinforcing bar, 21, L-shaped in cross section, is secured by one flange to the post by means of the bolts, 19, and has its other flange riveted to the corrugations as indicated at 22.

In Figs. 5, 6 and 7 there is shown an end for a gondola car similar to the construction illustrated in Figs. 1, 2 and 3, the end in this instance, however, being made of a single panel and it being shown applied to thin side walls, 40, with which no corner posts are associated. The side marginal portions of the panel are flanged around the sides, as indicated at 10, in the same manner as heretofore explained, and the corners are reinforced by means of the L-shaped bars, 11, and the angle irons, 14, corresponding to the parts similarly numbered in Fig. 3. Around the top of the car is a bulb angle, 41, one flange of which is horizontal and one flange of which is vertical and arranged behind the upper flat marginal portion of the panel, the panel and this vertical flange being fastened together by rivets, 42. The panel is flanged outwardly at its lower end as indicated at 43 and is riveted to the upper flange of the end sill, 44, or other suitable floor structure.

While I have illustrated and described with particularity only a few preferred forms of my invention, I do not desire to be limited to the particular details thus illustrated and described; but intend to cover all forms and arrangements coming within the definitions of my invention constituting the appended claims. Furthermore, I desire to have it understood that the word "bent" is used in the claims more in the sense of shape or contour rather than in the sense of a particular process employed in producing such shape. In other words, by "bent" I mean something that is not straight.

I claim:

1. The combination with the side walls of a car body, of a sheet metal end having its side marginal portions flanged to engage with the outer faces of said side walls, said end having transverse corrugations bent lengthwise so as to bring the ends on the inner side of the plane of the sheet and the middle portion on the outer side of the plane of the sheet, and reinforcing elements lying within the corners formed by the said walls and said end and secured respectively to the end portions of the corrugations and to the said side walls.

2. The combination with the side walls

of a car body, of a sheet metal end having its side marginal portions flanged to engage with the outer faces of said side walls, said end having transverse corrugations at least the ends of which lie on the inner side of the plane of the sheet, and reinforcing elements lying within the corners formed by the said walls and said end and secured respectively to the end portions of the corrugations and to the said side walls. 75

3. The combination with the side walls of a car body, of a sheet metal end having its side marginal portions flanged to engage with the outer faces of said side walls, said end having transverse corrugations bent lengthwise so as to bring the ends on the inner side of the plane of the sheet and the middle portion on the outer side of the plane of the sheet, and vertical reinforcing bars lying within the corners formed by the said walls and said end and secured respectively to the end portions of the corrugations and to the said side walls. 80

4. The combination with the side walls of a car body, of a sheet metal end having its side marginal portions flanged to engage with the outer faces of said side walls, said end having transverse corrugations bent lengthwise so as to bring the ends on the inner side of the plane of the sheet and the middle portion on the outer side of the plane of the sheet, vertical metal bars lying within the corners formed by the said walls and said end and secured to said walls, and elements connecting said bars to the adjacent end portions of the corrugations. 90

5. The combination with the side walls of a car body, of a sheet metal end having its side marginal portions flanged to engage with the outer faces of said side walls, said end having transverse corrugations bent lengthwise so as to bring the ends on the inner side of the plane of the sheet and the middle portion on the outer side of the plane of the sheet, vertical angle irons lying within the corners formed by the said walls and said end and secured to said walls, and vertical bars secured respectively to said angle irons and to the adjacent end portions of the corrugations. 105

6. The combination with the side walls of a car body, of a sheet metal end having integral side marginal portions flanged to engage with the outer faces of said side walls, said end having transverse corrugations, and reinforcing elements lying within the corners formed by the said walls and said end and secured respectively to the end portions of the corrugations and to the said side walls. 120

7. The combination with the side walls of a car body, of a sheet metal end having integral side marginal portions flanged to engage with the outer faces of said side walls, said end having transverse corrugations, and vertical reinforcing bars lying 125

- within the corners formed by the said walls and said end and secured respectively to said sheet metal end at the end portions of the corrugations and to the said side walls.
5. 8. The combination with the side walls of a car body, of a corrugated sheet metal end having integral side marginal portions flanged to engage with the outer faces of said side walls, vertical metal bars lying within the corners formed by the said walls and said end and secured to said walls, and elements connecting said bars to the adjacent portions of the sheet metal end.
10. 9. The combination with the side walls of a car body, of a corrugated sheet metal end having its side marginal portions flanged to engage with the outer faces of said side walls, vertical angle irons lying within the corners formed by the said walls and said end and secured to said walls, and vertical bars secured respectively to said angle irons and to the adjacent end portions of the said sheet metal end.
15. 10. The combination with the side walls of a car body, of a sheet metal end having transverse corrugations bent lengthwise so as to bring the ends on the inner side of the plane of the sheet and the middle portion on the outer side of the plane of the sheet, and vertical reinforcing bars lying within the corners formed by the said walls and said end and secured respectively to the end portions of the corrugations and to the said side walls.
20. 11. The combination with the side walls of a car body, of a sheet metal end having transverse corrugations bent lengthwise so as to bring the ends on the inner side of the plane of the sheet and the middle portion on the outer side of the plane of the sheet, and vertical reinforcing bars lying within the corners formed by the said walls and said end and secured to said walls, and elements connecting said bars to the adjacent end portions of the corrugations.
25. 12. The combination with the side walls of a car body, of a corrugated sheet metal end, vertical metal bars lying within the corners formed by the said walls and said end and secured to said walls, and additional bars connecting said bars to the adjacent portions of the sheet metal end.
30. 13. The combination with the side walls of a car body, of a corrugated sheet metal end, vertical angle irons lying within the corners formed by the said walls and said end and secured to said walls, and vertical bars secured respectively to said angle irons and to the adjacent end portions of the said sheet metal end.
35. 14. The combination with the side walls of a car body, of a sheet metal end extending between and across the ends of said side walls, said end having transverse corrugations bent lengthwise so as to bring the ends on the inner side of the plane of the sheet and the middle portion on the outer side of the plane of the sheet, and reinforcing elements lying within the corners formed by said walls and said metal end and secured to the end portions of the corrugations and to said side walls.
40. 15. The combination with the side walls of a car body, of a sheet metal end extending between said walls, said sheet metal end having transverse corrugations bent lengthwise so as to bring the ends of the corrugations on the inner side of the plane of the sheet and the middle portions on the outer side of the plane of the sheet, and vertical reinforcing bars lying within the corners formed by said walls and said metal end and secured to the end portions of the corrugations and to said side walls.
45. 16. The combination with the side walls of a car body, of a sheet metal end extending between said side walls and having transverse corrugations bent lengthwise so as to bring the ends thereof on the inner side of the plane of the sheet and the middle portions on the outer side of the plane of the sheet, and reinforcing elements lying within the corners formed by said walls and said end, each of said elements having a flange portion lying against the end portions of the corrugations and parallel with the longitudinal elements of said end portions, said reinforcing elements being secured respectively to the end portions of the corrugations and to said side walls.

In testimony whereof, I sign this specification.

WILLIAM E. VAN DORN.
